UNITED STATES PATENT OFFICE.

APOLLONIO ZANELLA, OF RAY, ARIZONA.

TROLLEY-WIRE GUARD.

1,183,709.

Specification of Letters Patent.

Patented May 16, 1916.

Application filed October 29, 1915. Serial No. 58,648.

To all whom it may concern:

Be it known that I, APOLLONIO ZANELLA, a citizen of the United States, residing at Ray, in the county of Pinal and State of Arizona, have invented new and useful Improvements in Trolley-Wire Guards, of which the following is a specification.

The present invention relates to guards with the feed wires of electrically propelled vehicles employed in mines or in other places where the charged wires are so positioned as to be easily contacted by a person in proximity to the said wire, and the object of the invention is to provide such wires with a shield of non-electric conducting material to prevent persons or animals from coming in direct contact with the wire.

Other objects and advantages will appear as the nature of the invention is more fully understood, reference being had to the accompanying drawings in which there is illustrated a simple and satisfactory reduction of the improvement to practice.

In the drawings, Figure 1 is a side elevation of a portion of the guard constructed in accordance with the present invention showing the same applied to the wire showing the wire engaged by a trolley wheel. Fig. 2 is a transverse section approximately on the line 2—2 of Fig. 1. Fig. 3 is a similar section approximately on the line 3—3 of Fig. 1. Fig. 4 is a central longitudinal sectional view through the improvement. Fig. 5 is a detail sectional view illustrating the manner in which the hanger is attached to the shield. Fig. 6 is a perspective view; parts being broken away and parts being shown in section and illustrating the manner in which the hinged clamp is arranged upon the shield and engages the wires. Fig. 7 is a perspective view of a hinged clamp detached. Fig. 8 is a sectional view through the hinged clamp illustrating the plates thereof connected by a nut and bolt.

As is well known the leads or tunnels in a mine are seldom constructed at a height greater than the height of an ordinary man, and where electrically propelled cars, of the trolley or overhead system are employed the trolley wire being suspended from the upper wall or even from the side walls of the lead or tunnel is within close proximity to the miners or to other persons having business in the mines. This has frequently resulted in persons accidentally contacting with the energized feed wires, with dangerous results,

and it may therefore be considered the primary object of the present invention to provide a guard or shield in the nature of a cover for such wires which will prevent persons contacting with the same, but which shall in no way interfere with the contact of the trolley wheel with the said wire.

In the drawings the numeral 1 designates the feed wire of a trolley system, and this wire preferably has its opposite sides formed with longitudinally extending grooves 2.

My improved guard comprises a substantially U-shaped member constructed of some suitable insulated material and is designated by the numeral 3. The sides 4—4 of the member 3 are spaced a suitable distance from the opposite sides of the wire 1 and the ends of the sides are preferably flared outwardly as at 5. By this arrangement the trolley wheel 6 may freely engage with the wire 1 and also the space between the sides 4—4 of the member 3 is sufficient to accommodate the upper portion of the harp 7 upon which the trolley wheel 6 is rotatably mounted.

The member 3 may have interior reinforcements which are designated by the numerals 8—8 and these reinforcements may be of metal so that the sides 4 are maintained in proper spaced relation with each other. Passing centrally and longitudinally through the top or connecting portion of the inverted U-shaped member 3 is a rod 9, and this rod is adapted to provide a pintle for the butts 10 of hinge members 11 having their lower ends curved inwardly as at 13, so that the said portions 13 will engage with the upper portions of the wire 1, to the opposite sides thereof to permit the edges of the said portions 13 to be received in the grooves 2 of the wire. In order to secure the plates 12 of the hinge 11 upon the wire, one of the said plates is provided with a non-threaded opening which registers with a threaded opening in the second plate, and screws 14 for their threaded shank passing through the said opening and engaged with the threads of one of the openings. One of the sides 4 of the member 3 is formed with openings 15 which are of a greater area or diameter than that of the heads of the screws 14 and the openings 15 are adapted to register with the kerfed heads of the screws, so that an instrument such as a screw driver may be passed through the openings 15 to adjust the screws and to

100
105
110

regulate the pressure of the portions 13 of the hinge members 11.

It is, of course, to be understood, and illustrated in Fig. 8 of the drawings, headed 5 bolt members 16 may be employed in lieu of the screws 14, the shanks of the same passing through openings in the plates and having their ends engaged by nuts 17 and the nuts are so arranged with relation to 10 the rounded portions 13 of one of the plates of the hinge as to contact therewith and so prevent accidental rotation of the said nut.

In order to suspend the device the upper or connecting portion of the inverted 15 U-shaped member is provided, at spaced intervals with revolute bolts 18 received in suitable sockets 19 in the said upper portion of the member 3. These bolts may be provided with square wrench heads so that the 20 same may be rotated to engage in suitable sockets secured to the upper wall or ceiling of the lead or tunnel.

The hinge members are each centrally formed with outwardly extending downwardly rounded spring fingers 20, one of which being arranged to extend over each of the sides of each of said hinges, and these members contact with the inner sides 4 of the U-shaped member 3, assisting in 30 sustaining the said sides in proper spaced relation with each other.

Having thus described the invention what is claimed is:—

1. In combination with a feed wire, of a 35 guard of insulated material therefor, said guard having an open bottom, and its sides spaced from the sides of the feed wire, a clamping member secured to the top of the guard and impressing the opposite sides of 40 the feed wire for sustaining the feed wire approximately central in the guard; means

connected with the clamp for engaging with the sides of the guard for assisting in and maintaining the said sides in spaced relation with each other, and revolute hanger 45 members upon the top of the guard.

2. In combination with a feed wire, and a guard of insulated material surrounding the same, and said guard being approximately of an inverted U-shape in cross section, of a clamping member centrally secured to the guard and extending inwardly thereof and connecting the feed wire thereto, said clamping member including laterally arranged angularly disposed spring 55 fingers extending over the opposite sides of the clamping member and contacting with the inner and opposite sides of the guard.

3. The combination with a feed wire and a guard therefor which comprises an insulating member that is substantially of an inverted U-shape in cross section, of a rod member embedded in the central portion of the said guard, clamping members each including plates arranged side by side and 65 having one of their edges rounded to provide butts which engage with the rod, each of said plates having its lower edge rounded to engage with the opposite sides of the feed wire, securing means for each pair of plates 70 to hold the same in engagement with the wire, and spring fingers connected with the rod and disposed centrally of each of the clamping members and extending beyond the sides thereof to contact with the inner 75 sides of the guard.

In testimony whereof I have affixed my signature in presence of two witnesses.

APOLLONIO ZANELLA.
